UNITED STATES PATENT OFFICE

WILLIAM M. SCHOLL, OF CHICAGO, ILLINOIS

ORTHOPEDIC SHOE

Application filed April 2, 1925. Serial No. 20,049.

The invention relates to improvements in shoes and has especial reference to shoes for reforming the feet, or for maintaining them in their natural condition.

5 One of the objects of the invention is to improve shoes to conform more closely with the natural shape of the human foot and to restore the foot to its natural form.

Another object is to provide in shoes, 10 rigid steel shanks, under the longitudinal arch of the foot and to extend the shank to the rear of the heel portion thereby to provide a depression or opening in said rear portion to form a socket to receive the heel 15 of the wearer, to prevent the foot from sliding longitudinally of the shoe, and to provide with the inner sole of the shoe a resilient heel receiving cushion or socket to support the heel of the foot.

20 Another object is to provide a forward cushion connected with the front end of the steel shank and preferably arranged between said shank and the inner lining of the shoe to support the anterior metatarsal arch of 25 the foot.

A further object is to provide in a shoe a stiffening shank in the rear of the phalanges, extending back to the rear of the heel and a cushion pad overlying the front 30 end of the shank and extending under the rear articulation of the phalanges to yieldingly support the anterior metatarsal arch of the foot.

Other objects, advantages and benefits of 35 the invention will become apparent to a person skilled in the art from a consideration of the following description, when taken in conjunction with the drawings, wherein:

40 Figure 1 is a bottom plan view of a shoe with the outer sole removed, showing the shank in position under the inner sole of the shoe.

45 Figure 2 is a longitudinal section of the shoe with the enclosed shank.

Figure 3 is a transverse section taken on line III—III of Figure 1.

50 Figure 4 is a transverse section taken on line IV—IV of Figure 1.

In all the views the same reference characters refer to similar parts.

Reference numeral 10 is the outer sole of the shoe and 11 is the inner sole of the shoe. Between these soles the shank 12 is 55 contained. The upper or vamp 13 of the shoe is attached to the outer and inner sole in the usual manner.

The shank 12 extends to a point 15 at the rear of the heel 16 of the shoe. The 60 shank is provided with a heel receiving recess 17 to provide a socket with the inner sole 11 as at 18, thereby making a receptacle or recess for the heel of the wearer. The shank 12 is provided with a rib 19 to 65 stiffen it in its median portion. The front end of the shank terminates as at 20 and to the front end of the shank is secured a resilient yielding pad 21 of soft rubber, felt or the like, secured to the shank by rivets 70 22. These rivets extend through the inner sole, the pad, and the shank and hold the parts together. The pad is oval in contour and is intended to support the anterior metatarsal arch of the foot. The shank 12 is upwardly curved to underlie the longitudinal arch of the foot and does not extend into the region of the shoe underlying that portion of the foot which is bent in the act of walking. The rear end of the shank 12 may 75 also be fastened to the inner sole by rivets 24.

By building the shank and pad into the shoe structure and securing it to the inner sole and other parts of the shoe there is 80 no liability of its becoming displaced in use and shifting into undesirable positions.

The shoe is intended for persons who have chronic cases of fallen metatarsal arches, to be worn for protracted periods of time.

The steel shank described, extends substantially from the rear portion of the heel to a point near the articulation of the phalanges of the foot and secured to the front end thereof is a metatarsal arch support, 90 yielding in character and placed in proper position with relation to the shank and to other portions of the shoe.

I am aware that many changes may be made, and numerous details of construction 100

may be varied through a wide range without departing from the principles of this invention and I therefore do not purpose limiting the patent granted hereon, otherwise than necessitated by the claims.

Having described my invention what I claim as new and desire to secure by Letters Patent is:—

1. In a shoe, a built in stiffening shank 10 extending from the rear of the heel to the front end of the longitudinal arch and having a heel receiving recess in the heel portion to provide a socket for the heel of the wearer; a yielding pad at the front end of the shank underlying the anterior metatarsals of the foot; and an inner sole overlying the shank and pad and having a heel receiving recess conforming to the shank recess.

2. A shoe having an inner and an outer sole; a built in stiffening shank extending 20 from the rear of the heel substantially to the front end of the longitudinal arch of the foot and having a recess to receive the heel; and a yielding cushion or pad at the 25 front end of said shank and extending under the ball of the foot, said shank and pad being arranged between the aforesaid soles of the shoe.

3. A shoe having a built in stiffening shank 30 underlying the longitudinal arch and the heel of the foot, a cushion or pad at the front end of said shank and underlying the transverse arch of the foot; and a covering for said shank and pad, said shank, pad and covering being riveted together.

4. A shoe having a bottom comprising an inner sole and an outer sole, a metallic shank arranged between said soles and extending from the rear of the heel to the front end 40 of the longitudinal arch, said shank being slightly curved transversely intermediate its ends and having a heel receiving recess in the rear end thereof, and a pad of yieldable material secured to the top of the front end 45 of said shank with a portion thereof extending beyond the front end of the shank, which pad is substantially wedge-like in longitudinal vertical section, said pad being of sufficient thickness to space the inner sole 50 from the outer sole in a manner to form a straighter angle in the inner sole than that in the outer sole immediately below the same.

5. A shoe having a bottom comprising an 55 inner sole and an outer sole, a metallic shank arranged between said soles and extending from the rear of the heel to the front of the longitudinal arch, said shank being slightly curved transversely intermediate its ends, 60 the heel end of said shank having a heel receiving recess therein, the recessed heel end of said shank providing a pocket for supporting a heel of the foot below the surface of the shank, and a pad of yieldable material secured to the front end of said shank

with a portion thereof extending beyond the front end of the shank, said pad being wedge-like in longitudinal vertical section.

6. A shoe having a bottom comprising an inner sole and an outer sole, a metallic shank 70 extending from the rear of the shoe bottom to the front end of the longitudinal arch, a yielding pad attached to and extending forwardly of said shank to underlie the metatarsal arch of the foot, an inner sole 75 covering the shank and pad, and fastening means passing through the shank, pad and inner sole.

7. A shoe having an inner sole, an outer sole having an abutment back of the breast line, and a metal shank positioned between the inner and outer soles arranged under the longitudinal arch and heel of the wearer, the said shank having a depressed portion forming a heel-receiving recess into which the inner sole will be depressed by the wearer's heel, the forward wall of the depressed portion forming an abutment for engagement with the said abutment of the outer sole.

In testimony whereof I have hereunto subscribed my name.

WILLIAM M. SCHOLL.
